US00D941848S

(12) **United States Design Patent** (10) **Patent No.:** **US D941,848 S**
Mathison et al. (45) **Date of Patent:** **** Jan. 25, 2022**

(54) **DISPLAY SCREEN OR PORTION THEREOF WITH GRAPHICAL USER INTERFACE**

(71) Applicant: **Kilpatrick Townsend & Stockton LLP**, Atlanta, GA (US)

(72) Inventors: **Mark P. Mathison**, Walnut Creek, CA (US); **Trajan E. Unger**, Fairfax, CA (US)

(73) Assignee: **Kilpatrick Townsend & Stockton LLP**, Atlanta, GA (US)

(**) Term: **15 Years**

(21) Appl. No.: **29/800,493**

(22) Filed: **Jul. 21, 2021**

Related U.S. Application Data

(63) Continuation of application No. 29/658,973, filed on Aug. 3, 2018, now Pat. No. Des. 928,800.

(51) **LOC (13) Cl.** **14-04**

(57) **CLAIM**

The ornamental design for a display screen or portion thereof with graphical user interface, as shown and described.

DESCRIPTION

FIG. 1 is a front view of a portion of a display screen with graphical user interface according to a first embodiment of our new design; and,

FIG. 2 is a front view of a portion of a display screen with graphical user interface according to a second embodiment thereof.

The wavy dashed-line rectangle illustrates the perimeter of a portion of a display screen and forms no part of the claimed design.

The flags illustrated in a faded grayscale in FIGS. 1 and 2 form no part of the claimed design.

The text shown in broken lines forms no part of the claimed design.

1 Claim, 2 Drawing Sheets
